WALDO F. FOLLETT, OF NEW HAVEN, CONNECTICUT, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,117,559.

Specification of Letters Patent. Patented Nov. 17, 1914.

Application filed November 12, 1912. Serial No. 730,875.

To all whom it may concern:

Be it known that I, WALDO F. FOLLETT, a citizen of the United States, residing at New Haven, in the county of New Haven 5 and State of Connecticut, have invented certain new and useful Improvements in Railway Signaling, of which the following is a specification.

My invention relates to railway signaling 10 systems.

I will describe one form of railway signaling system embodying my invention and will then point out the novel features thereof in claims.

15 In the accompanying drawings Figure 1 is a diagrammatic view showing one form of railway signaling system embodying my invention, and Fig. 2 is a view showing diagrammatically that the common wire for 20 each block section is electrically disconnected from the common wire for each adjacent block section.

Referring to the drawing, 1, 2, 3 and 4 25 designate four parallel tracks of a railway, here shown as being an electric railway. It is understood that the railway is provided with a suitable source of propulsion current and with a third rail or trolley wire, but for the sake of simplicity these parts are omitted 30 from the drawing. The track rails of each track are divided into block sections L, K and N by any suitable means; as here shown these block sections are formed by insulated joints 66 in both track rails of each track.

35 Since the railway is an electric railway, the track rails are preferably included in the circuit for the propulsion current. I provide inductive bonds 55 by means of which the propulsion current is conducted around 40 the insulated joints 66 from the track rails of one block section to the track rails of the adjacent block sections.

Traffic along the tracks 1, 2, 3 and 4 is 45 normally in the direction indicated by the arrows in these tracks. Traffic through block section K over tracks 1 and 3 is governed by signals S' and S³; traffic through block section K over tracks 2 and 4 is governed by signals S² and S⁴; similarly traffic 50 over tracks 1 and 3 through block section L is governed by signals S⁶ and S⁵; and traffic over tracks 2 and 4 through block section N is governed by signals S⁷ and S⁸. Each of 55 these signals is adapted to give three indications, namely, "danger," "caution" and

"clear"; as here shown, each signal comprises two arms, a home arm *h* and a distant arm *d*, although I do not wish to be limited to this particular type of signal. It is understood that one arm three-position signals 60 may equally well be employed. It is also understood that regardless of the type of signal employed, each signal is provided with two controlling circuits, viz., a caution indication circuit and a clear indication circuit. In the case of two-arm two-position signals as shown in the drawing, the caution indication circuit controls the controlling apparatus for the home arm *h*, and the clear indication circuit controls the controlling apparatus for the distant arm *d*. 65

Alternating signaling current for the signaling system is supplied by power mains *M* extending along the trackway, which mains are supplied from a suitable source, such as 70 a generator 77. The signaling current should differ in character from the propulsion current; if the propulsion current is alternating, then the signaling current differs therefrom preferably in frequency. In 75 the present case I will assume that the propulsion current is 25 cycle current and that the signaling current is 60 cycle current.

Located adjacent each set of signals is a 80 transformer *T* or *T'*, whose primary is connected with the power mains *M* and whose secondary is connected with local distributing wires *X* and *Y* or *X'* and *Y'*.

Each block section of each track is provided with a track circuit comprising as 85 usual a source of current connected with the track rails adjacent one end of the block section and a track relay connected with the track rails adjacent the other end of the block section. For example, the source of 90 current for the track circuit for block section K of track 3 is a transformer 56 whose primary is connected with wires *X* and *Y* and whose secondary is connected with the track rails by wires 58 and 59. The track 100 relay *R*² of this track circuit is as here shown of a polyphase type comprising one winding *W'* connected with the track rails by wires 60 and 61 and another winding *W* connected with wires *X'* and *Y'* by wires 62 105 and 63. This relay is of a frequency selective type, that is, it will respond to the frequency of signaling current in its track winding *W'* to close its contacts but will not respond to the propulsion current in its 110

track winding to close its contacts. Several types of relay of this character are known in the art and no further explanation is required. The sources of current for block sections K of tracks 1, 2 and 4 are respectively transformers 57, 64 and 65, and the track relays for these track circuits are respectively relays R', R² and R⁴, each of which relays may be similar to relay R³.

For the control of each signal I provide a signal relay. Signal S³ is controlled by relay B, signal S' by relay D, signal S² by relay F and signal S⁴ by relay H. Each of these signal relays is of a 3-position type and as here shown is of a single phase type comprising two members, an armature *a* and a field winding *f*. Each of these relays is so arranged that when the armature *a* is in one extreme position the contact fingers engage the upper contact points; when the armature is in the other extreme position, the contact fingers engage the lower contact points; and when the armature occupies the middle position all the contacts are open.

The circuit for home arm *h* of each signal is controlled by the upper contact fingers 67 and 68 of the corresponding relay, and the circuit for distant arm *d* is controlled by the two lower contact fingers 69 and 70.

For example, the circuit for the home arm *h* of signal S³ is from wire Y' through wire 13, upper or lower point of contact 67, wire 14, controlling apparatus for home arm *h*, wire 15, upper or lower point of contact 68, wire 16 to wire X'. The circuit for the distant arm *d* of signal S³ is from wire Y' through wire 13, upper point of contact 69, wire 17, controlling apparatus for arm *d*, wire 18, upper point of contact 70, wire 16 to wire X'. It will be seen therefore that when the armature *a* of relay B occupies its middle position the circuits for both arms of signal S³ are open so that the signal then indicates danger; when the armature *a* occupies its lower position so that the lower points are engaged by the contact fingers, the circuit for home arm *h* is closed and the circuit for the distant arm *d* is open so that the signal then indicates caution; but when armature *a* occupies its other extreme position so that the upper points of the relay are engaged by the contact fingers, the circuits for both arms are closed so that the signal then indicates clear. The circuits for each of the signals S', S² and S⁴ are similar to those just traced for signal S³ hence they need not be traced herein. The field winding *f* of each signal relay is connected with wires X, Y, or X', Y'. For example the field winding *f* of relay B is connected with wires X', Y' by wires 78 and 79. The armature winding *a* of each signal relay is connected with a line circuit extending through the block section K and energized from the source of signaling current at the opposite

end of the block section. Each of these line circuits is provided with a pole changer P³, P', P² or P⁴ respectively, for reversing the polarity of the current in the line circuit, these pole changers being operatively connected respectively with the home arm *h* of signals S⁵, S⁶, S⁷ and S⁸. Each line circuit also includes a transformer A, C, E or G. Each line circuit comprises a line wire individual to that circuit and a common wire 7, which common wire is common to all of the line circuits for block section K and is not connected with the common wire of either of the adjacent block sections L or N. The fact that the common wire 7 of each block section is electrically disconnected from the corresponding wire of each adjacent block section is indicated in Fig. 2. The line circuit for relay B includes pole-changer P³ and transformer A. The circuit of the primary of this transformer is as follows—from wire Y through wire 51, contact of pole changer P³, wire 52, primary of transformer A, wire 53, contact of pole changer P³, wire 54, to wire X; the secondary circuit for this line circuit is from the secondary of transformer A through wires 5 and 6, common wire 7, wires 8 and 9, contact of track relay R³, wire 10, armature *a* of relay B, wire 11, contact of relay R³, wire 12 to the secondary of transformer A. The line circuit for relay D is similar to that just traced for relay B and includes pole changer P', transformer C, line wires 27 and 7, and the contacts of track relay R'. Similarly the line circuit for relay F includes pole changer P², transformer E, line wires 47, and 7, and the contacts of track relay R². The line circuit for relay H similarly includes pole changer P⁴ transformer G, line wires 38 and 7, and the contacts of track relay R⁴.

The operation of the system may be sufficiently explained by explaining the effect on the circuits and apparatus of the passage of a car or train along track 3. When the block sections L and K of track 3 are unoccupied, as shown in the drawing, track relay R³ is closed thereby holding closed the line circuit for signal relay B. Home arm *h* of signal S⁵ is in the inclined position so that pole changer P³ is in such position that the polarity of the current in the line circuit for relay B causes the upper points of this relay to be engaged by the contact fingers so that signal S³ indicate clear. If now, a car or train enters block section K from block section N it deenergizes track relay R³, thereby opening the line circuit for relay B the armature of which then moves to its middle position; this opens the circuits for both the home and distant arms of signal S³ so that this signal changes to danger indication. As the car or train passes out of block section K into block section L it similarly causes signal S⁵ 130

to change to danger indication whereby reversing pole changer P^3 . Track relay R^3 now closes thereby closing the line circuit for signal relay B but the polarity of the current in this line circuit having been reversed by pole changer P^3 , this relay is energized in such direction that its lower points are engaged by the contact fingers thereby closing the circuit for home arm h 10 of signal S^3 , but holding open the circuit for the distant arm d of this signal so that signal S^3 then indicates caution. As the car or train passes out of block section L it causes signal S^3 to change to caution indication 15 thereby again reversing pole changer P^3 , so that the polarity of the current in the line circuit for signal relay B is then such as to cause the upper points of this relay to be closed thereby causing signal S^3 to again indicate clear. The operation of the apparatus for each of the other three tracks is the same as that which I have just explained for track 3, hence no further explanation is necessary. 20

25 The circuits which I have hereinbefore explained are so arranged that a false clear signal indication cannot be caused by broken wires, crosses or electromagnetic or static induction. I will now describe the effect on 30 the system of these abnormal conditions. If any one of the line wires 12, 27, 47 or 38 should become open, the 3-position signal relay controlled by such wire will be de-energized so that its contacts will assume 35 their middle position, thereby causing the signal controlled by that relay to indicate danger. If the common wire 7 becomes open the effect is as follows—if block sections K and L of track 3 are unoccupied, 40 current will pass from the secondary of transformer A, through wires 5 and 6, wire 34 to the point where it divides into wires 35 and 44, through wires 35 and 44 in multiple, contacts of relays R^4 and R^2 , wires 36 45 and 45 in multiple, armatures of signal relays H and F in multiple, wires 37 and 46 in multiple, contacts of track relays R^4 and R^2 in multiple, wires 38 and 47 in multiple to secondaries of transformers G and E, 50 wires 32 and 43 in multiple, wire 33, wire 8 to point where it divides into wires 9 and 24, thence through wire 9, contact of relay R^3 , wire 10, armature of relay B, wire 11, contact of relay R^3 , wire 12 to secondary of 55 transformer A. It will be seen, therefore, that if common wire 7 is open and block sections K and L of track 3 are unoccupied, current from transformer A still passes through armature of relay B in the normal 60 direction so that this relay is still energized to cause signal S^3 to indicate clear. Current from the secondary of transformer C passes through wire 23, then it flows in common with current from transformer A through 65 wires 6 and 34, wires 35 and 44 in multiple, contacts of relays R^4 and R^2 in multiple, wires 36 and 45 in multiple, armatures of signal relays H and F in multiple, wires 37 and 46 in multiple, contacts of relays R^4 and R^2 in multiple, wires 38 and 47 in multiple, 70 secondaries of transformers G and E in multiple, wires 33 and 8; from thence the current from transformer C alone passes through wire 24, contact of relay R' , wire 25, armature of relay D, wire 26, contact of relay R' , wire 27 to secondary of transformer C. It will be seen, therefore, that current from transformer C still passes through signal relay D in the normal direction so that this relay is still energized to 75 cause signal S' to indicate clear. Current from transformer A cannot energize relay D because wire 27 leading from that relay does not connect with transformer A; and similarly current from transformer C cannot 80 energize relay B because wire 12 leading from that relay does not connect with transformer C. Hence, when common wire 7 is open and block sections K and L of tracks 3 and 1 are unoccupied, the signals are not 85 affected. 90

If, while common wire 7 is open, a train enters either track 3 or 1 of block section K, signal S^3 or S' for that track will change to danger and the other signal S' or S^3 will 95 not be affected. When such train passes from block section K into block section L, the corresponding signal S^3 or S' changes to caution. For example, assume that track 3 of block section L is occupied. The polarity of transformer A is then reversed 100 with respect to transformer C, and current then flows from the secondary of transformer A through wire 12, contact of relay R^3 , wire 11, armature of relay B, wire 10, contact of relay R^3 , wires 9 and 24, contact of relay R' , wire 25, armature of relay D, wire 26, contact of relay R' , wire 27, secondary of transformer C, wires 23 and 5 to 105 secondary of transformer A. The direction of this current in relay B is such as to energize that relay in such direction as to cause signal S^3 to indicate caution, and the direction of this current in relay D is such as to energize that relay in such direction as to cause signal S' to indicate clear. Hence, 110 the proper operation of these signals is not interfered with, and the opening of common wire 7 cannot cause a false clear signal. The circuits for signal relays H and F from 115 transformers G and E in case common wire 7 becomes open are similar to those just explained for signal relays B and D. 120

Assume that any one of the wires 12, 27, 47 or 38 becomes crossed with the common wire 7, as for example, that line wire 12 becomes connected with common wire 7, as indicated at 71 on the drawing. Current will then flow from the secondary of transformer A through wires 5, 6 and 7 to the cross 71, 125 130

at which point it divides, part passing through wires 7, 8 and 9, contact of relay R^3 , wire 10, relay B, wire 11, contact of relay R^3 , wire 12 to the cross 71; thence 5 through wire 12 to the secondary of transformer A; the remainder of the current will flow from wire 7 through the cross 71 to wire 12, thence through wire 12 to transformer A. If the cross 71 is of sufficiently 10 low resistance such a large portion of the current will pass through the cross that the signal relay B will be deenergized and signal S^3 controlled thereby will indicate danger. If however the cross 71 is not of 15 sufficiently low resistance, the operation of the system will not be interfered with. A similar condition would exist in case of a cross between common wire 7 and any one of the remaining line wires.

20. Assume now that a cross exists between any two of the wires 12, 27, 47 and 38, for example, between wire 12 and 27 as indicated at 72 on the drawing. Current would then flow from the secondary of transformer 25 A through wires 5, 6, 7, 8 and 9, contacts of relay R^3 , wire 10, relay B, wire 11, contact of relay R^3 , wire 12, to the point of cross 72; if transformer C is energized with the same 30 polarity, current will flow from the secondary of this transformer through wires 23, 6, 7, 8 and 24, contact of relay R' , wire 25, relay D, wire 26, contact of relay R' , wire 27 to the point of cross 72; these two 35 currents at the point 72 have the same polarity and the same potential, hence, they will flow through their respective wires 12 and 27 to the secondaries of their respective 40 transformers A and C. Hence, when the transformers A and C have the same polarity the cross 72 will have no effect on the signaling system. Assume however, 45 that the cross 72 exists and that the polarity of the transformers A and C is opposite; for example, assume that the polarity of transformer A remains as before but that the 50 polarity of transformer C is reversed by the presence of a car or train in block section L of track 1. Then current attempts to flow as hereinbefore explained from transformer A through wires 5, 6, 7, etc., to relay B and wire 12 to cross 72; at the same time current will attempt to flow from the 55 secondary of transformer C through wire 27 to the point 72. These two currents have opposite polarity at the point of the cross 72, so that the current from transformer A which was supposed to have passed through relay B is checked by the counter current through wire 27, and it passes instead 60 through wires 5 and 23 to the right hand of the secondary of transformer C, through this secondary to wire 27 to cross connection 72, wire 12, back to the left hand side of the transformer A, with the result that the two 65 transformers A and C are short circuited

and practically no current passes through the signal relays B or D. These relays are therefore deenergized causing signals S^3 and S' to indicate danger.

I will now describe the effect on the 70 signalling system of electromagnetic induction from an adjacent alternating current power line. Assume that such power line extends along the railway parallel therewith and that it is carrying a heavy 25 cycle propulsion current. This current will create an induced voltage upon the line circuits of the signal system by electro-magnetic induction. The strength of the induced voltage is dependent upon the strength 75 of the propulsion current, the distance between the propulsion lines and the signal lines, and the continuous length of the signal lines. In order to break the continuity 80 of the signal lines and thereby limit the possible values of the induced voltage, the signal lines for each block section, including the common wire 7 are made electrically independent of the signal lines for the adjacent block sections as hereinbefore explained. Assume that the line circuits are 85 sufficiently insulated from the ground to withstand this impressed voltage and also assume that at a given instant the induced current in the line circuits is flowing in the 90 direction indicated by the arrow 73. This induced current has a tendency to flow through wire 12, contact of relay R^3 , wire 11 to armature a of relay B; simultaneously an equal induced current has a tendency to 95 flow through wire 7 in the direction of the arrow 73, through wires 8 and 9, contact of relay R^3 , wire 10 to the other terminal armature a of relay B. These two currents will neutralize at the armature of relay B, hence, no 100 induced current would flow through this armature, and the induced current would have no effect on the signaling system. A similar condition would exist as to the three 105 remaining line circuits and signal relays.

Assume that the conditions electrically 110 are the same as just described with the exception that line wire 12 is grounded at the extreme ends of the block section, as for example, at the points 74 and 75. When the 115 current surge is in the direction indicated by arrow 73, the induced current would neutralize as heretofore explained but there will be another circuit established by the induced current as follows—from wire 12 to the ground at point 75, thence through the ground to point 74 and back to wire 12; also there will be a similar circuit established from wire 7 through wires 8 and 9, contact of relay R^3 , wire 10, relay B, wire 11, contact of relay R^3 , wire 12 to the ground at point 75, thence through the ground to point 74, to wire 12, secondary of transformer A, wires 5 and 6 to wire 7. Thus an 120 induced current flows through the armature 125 of relay B. The effect of this induced current 130 is to deenergize relay B, and the signal lines are thus short circuited.

of relay B. When a car or train occupies block K of track 3, this current will not affect the relay B because the contacts of track relay R³ will be open thus interrupting the circuit for the induced current just recited. Assume now that with the conditions just described, block section K is free but that a car or train occupies block section L of track 3, thereby changing the 10 polarity of the line circuit of signal relay B; this would under normal conditions cause signal S³ to indicate caution. Since the contacts of track relay R³ are now closed the induced current would now pass through the 15 armature of relay B as just explained. The conditions which now exist would be a 60 cycle signaling current and a 25 cycle propulsion current in both the field and the armature of relay B, the 60 cycle signaling 20 current being the normal energy supplied from the signal system. The 25 cycle propulsion current would pass through the armature of relay B, as cited above, and in passing through transformer A would cause 25 cycle energy in the power wires X and Y, which, in turn, would cause 25 cycle current in the tracks through the track transformers 56 and 57, and through transformer T into the power mains M, thence through transformer T' 25 into wires X' and Y', and thence into the field of relay B. The effect of this would be to reverse the torque of the armature of relay B. At the same time, the 25 cycle energy in the frequency track relay would 30 cause the contacts of the track relay to open, thus deenergizing relay B. The interrupting of the circuit through the armature of relay B would also interrupt the induced current, eliminating the effect of 25 35 cycle energy upon the instruments in question, and they would immediately assume their former position by the 60 cycle energy present. With the establishment of the former position of the instruments, the 25 cycle circuit would be reestablished. Thus it 40 will be seen that the contacts of relay B would vibrate between this former position and neutral position, thus causing the signal S³ to give either the caution indication 45 or danger indication.

At the instant when the direction of the surge of induced current in the line wires is as indicated by arrow 76, the effect on the signaling system would be the same as hereinbefore described, except that the direction of the flow of the current would be reversed at the same given instant.

As for static induction the signal line wires would be continuously charged statically from the adjacent propulsion line up to a voltage dependent upon the voltage of such line and upon the break-down insulation resistance of the line wires of the signaling system. By the introduction of 60 lightning arresters having a suitable pre-

determined break-down resistance, which resistance is lower than the break-down resistance of the signal line wires, these line wires could be constantly drained of the voltage impressed statically above the break-down point of the arresters. 70

Although I have herein shown and described only one form of signaling system embodying my invention, it is understood that various changes and modifications may 75 be made therein within the scope of the appended claims without departing from the spirit and scope of my invention.

Having thus described my invention, what I claim is:—

1. In combination, a block section of a railway track, a signal located adjacent the entrance end of the section and adapted to give three indications, power mains extending through the section, a source of alternating signaling current for said power mains, a main transformer located adjacent each end of the section, the primary of each main transformer being connected with said power mains, electromagnetic means for controlling said signal and comprising two windings one of which is constantly connected with the secondary of the main transformer at the entrance end of the section, a line circuit comprising two line wires connected with the other winding of said electromagnetic means and extending through the section, a line transformer whose primary is connected with the secondary of the main transformer at the exit end of the section and whose secondary is connected with said line wires, means for reversing the connection of the primary of the line transformer with the secondary of the last-mentioned main transformer, 100 said electromagnetic means being responsive to said reversals of connection, and a track circuit for the section including a track relay for controlling said line circuit. 105

2. In combination, a railway comprising two parallel tracks over which traffic moves in the same direction, a block section for each track, a signal for each block section adapted to indicate danger, caution and clear, a three-position signal relay for the 110 control of each signal, a source of alternating signaling current, a line circuit for each signal relay each comprising a line wire individual to such circuit and a common wire common to both circuits, a transformer for 115 each line circuit whose primary is connected with said source of signaling current and whose secondary is connected with the line circuit, a pole-changer for each line circuit for reversing the current in the line circuit with respect to the source, and a track circuit for each block section each including a track relay for controlling the line circuit of such block section. 120

3. In combination, a railway comprising 130

- two parallel tracks over which traffic moves in the same direction, a plurality of successive block sections for each track, the block sections of each track being substantially oppositely located, signals for the block sections adapted to indicate danger, caution and clear, a three-position signal relay for the control of each signal, a source of alternating signaling current, a line circuit for each signal relay each line circuit comprising a line wire individual to such circuit and a common wire common to the line circuit of the oppositely located block section of the other track, a transformer for each line circuit whose primary is energized from said source of signaling current and whose secondary is connected with the line circuit, means controlled by each signal for reversing the current in the line circuit for the block section in the rear relative to the said source, and a track circuit for each block section each including a track relay for controlling the line circuit of such block section.
4. In combination, a railway comprising a plurality of parallel tracks, a block section for each track, a signal for each block section adapted to give three indications, a three-position signal relay for each signal for the control thereof, a source of alternating signaling current, a line circuit for each signal relay each comprising a line wire individual to such circuit and a common wire common to all of the line circuits, a transformer for each line circuit whose primary is connected with said source of signaling current and whose secondary is connected with the line circuit, a pole changer for each line circuit for reversing the current in the line circuit with respect to the source, and a track circuit for each block section each including a track relay for controlling the line circuit of such block section.
5. In combination, a railway comprising a plurality of parallel tracks, each track being divided into a plurality of successive block sections and the block sections of each track being substantially opposite those of the other track or tracks, signals for the block sections adapted to indicate danger, caution and clear; a three-position signal relay for the control of each signal, a line circuit for each signal relay extending through the block section, a source of alternating current, a transformer for each line circuit having its primary energized from said source and its secondary connected with the line circuit, each line circuit comprising a line-wire individual to the circuit and another line wire common to the line circuits of the opposite block sections, a pole-changer included in each line circuit and controlled by the signal for the block section next in advance, and a track relay connected with the

track rails of each block section for controlling the line circuit of the block section. 65

6. In combination, a railway comprising a plurality of parallel tracks, each track being divided into a plurality of successive block sections and the block sections of each track being substantially opposite those of the other track or tracks, signals for the sections, a line circuit for each block section of each track extending through the block section, each line circuit comprising a line wire individual to the circuit and another line wire common to the line circuits of the opposite block sections, said common wire for each set of block sections being electrically insulated from the common wires for the adjacent sets of block sections, means controlled by each line circuit for controlling the signal for the corresponding block section, and a track relay connected with the track rails of each block section for also controlling the signal for the block section. 75 80 85

7. In combination, a railway comprising a plurality of parallel tracks, each track being divided into a plurality of successive block sections and the block sections of each track being substantially opposite those of the other track or tracks, signals for the sections, a line circuit for each block section for the control of the signal for such section, each line circuit extending through the section and comprising a line wire individual to the circuit and another line wire common to the line circuits of the opposite block sections, the said common wire for each set of oppositely located block sections being electrically insulated from the common wires for the adjacent sets of block sections. 90 95 100

8. In combination, a railway comprising a plurality of parallel tracks, each track being divided into a plurality of successive block sections and the block sections of each track being substantially opposite those of the other track or tracks, signals for the sections, a line circuit for each block section for the control of the signal for such section, each line circuit extending through the section the line circuits for each set of oppositely located block sections being electrically insulated from the line circuits for the adjacent sets of block sections. 105 110 115

9. In combination, a railway comprising two tracks over which traffic moves in the same direction, a block section for each track, a signal for each block section and adapted to give three indications, electromagnetic means for each signal for the control thereof, a source of alternating signaling current, a line circuit for the electromagnetic means for each signal, each line circuit comprising a line wire individual to the circuit and a common wire common to both circuits, a transformer for each line 120 125

circuit whose primary is connected with said source and whose secondary is connected with the common wire and with the line wire individual to the circuit, a pole-changer 5 for each line circuit for reversing the connection of the primary of the corresponding transformer thereof with the source, each electromagnetic means being responsive to such reversals, and a track circuit for

each block section including a track relay 10 for controlling the line circuit for the section.

In testimony whereof I affix my signature in presence of two witnesses.

WALDO F. FOLLETT.
